LOOP FOR RADIORECEPTION

Filed March 29, 1924

Inventor:
Ralph H. Langley,
by *Alexander S. Langley*,
His Attorney.

UNITED STATES PATENT OFFICE.

RALPH H. LANGLEY, OF SCHENECTADY, NEW YORK, ASSIGNOR TO GENERAL ELECTRIC COMPANY, A CORPORATION OF NEW YORK.

LOOP FOR RADIORECEPTION.

Application filed March 29, 1924. Serial No. 702,944.

My present invention relates to the type of antenna for radio reception known as a loop, and more particularly to loops which are adapted to be readily rotated and are of a 5 size convenient for indoor use.

One of the objects of my invention is to provide an efficient form of receiving loop which may be easily constructed. A further object of my invention is to provide a loop 10 which will have a maximum efficiency for a predetermined maximum available space and maximum predetermined value of inductance.

An indoor loop antenna must be a reasonably small structure and should be arranged 15 preferably to rotate on a vertical axis through an angle of at least 180 degrees. The total space required for the loop therefore is an imaginary vertical cylinder whose diameter is the horizontal dimension of the loop, and 20 whose height is the vertical dimension of the loop. In the past loops have usually been constructed in substantially flat form with more or less concentrated windings. The turns are usually wound quite close together 25 sometimes being separated only by the insulation on the wire itself. With such a winding the inductance is very closely proportional to the square of the number of turns. The number of turns therefore is 30 quite definitely limited by the fixed value of the inductance which cannot be exceeded if the desired range of wave lengths for which the loop is to be employed is to be covered.

Since the loop requires for its rotation all 35 of the space occupied by the imaginary cylinder mentioned previously, the space required for the loop will not be increased if the turns instead of being fairly close together as in other constructions, are spaced apart and distributed around the circumference of the 40 imaginary cylinder. I have found that by spacing the turns in this way a loop which will operate in a given space may be made much more efficient than when the turns are 45 concentrated, or the spacing between turns is very small. When the turns are spaced in this way it will be found that the inductance of the winding is no longer proportional to the square of the number of turns, but that 50 the loop may have several more turns than a concentrated winding before the fixed value of the inductance is reached. In the conventional type of loop where the turns are close together and all of the same size or nearly 55 so the area inside of the turns is a fair measure

of the pick up value of the loop. For example, a loop 48" square would have an area of 2,304 square inches, while a loop 33" square, or 30 per cent smaller, would have an area of only about 1,089 square inches 60 and would be less than half as effective. When the turns are spread out, as described, the pick up value is no longer proportional to the area. In the first place the turns no longer all have the same area and in addition 65 several extra turns are obtained for the same value of inductance. The pick up measure of such a loop is more nearly proportional to the turn-area, that is the number of turns multiplied by the average area included in 70 each turn.

In a radio receiving set with proper amplification it will be found that a loop having a certain value of turn area will give satisfactory performance. A larger loop will not 75 give any greater distance or stronger signal. The chosen size will be large enough to receive any signal which has a reasonable ratio to the air noises and set noises which limit the range and sensitiveness of every receiver. I 80 have found that a spaced turn cylindrical loop having the same turn area and inductance as a flat loop of the usual type having the necessary turn area to operate the receiver, can be made which will require for its operation less 85 than one-third the space of the flat loop. The spaced turn loop of cylindrical form has the additional advantage that on account of the spacing of the turns the losses are from one-half to one-third as great as in the equivalent 90 flat loop. These low losses not only permit much greater sensitivity or sharper tuning, but also increase the effectiveness of the loop as a pick up device.

The novel features which I believe to be 95 characteristic of my invention are set forth with particularity in the appended claims. My invention itself, however, both as to its organization and method of operation will best be understood by reference to the following description taken in connection with the accompanying drawing in which I have shown in perspective one form of my invention.

I have shown in the drawing a loop which is 105 wound over two end supports of substantially circular form. These supports each comprise two segments of rings 1 and 2, which are secured to a central cross bar 3 by means of rods 4. The two end supports are held in 110

spaced relation by means of four spaced vertical rods 5 and a central rod 6, which serves as a shaft. The ends of this shaft 6 are supported by bearings 7, which in turn may be secured to a supporting structure in any desired way.

- The turns of the loop are wound over this form, as indicated, the vertical portions forming elements of the imaginary cylinder and 10 the ends of the loop are secured to the central cross bar 3 of the top support and connected to two rings 8, of conductive material, which are mounted on the shaft 6. Brushes 9, which bear upon these rings 8 serve to conduct the 15 current received on the loop to the receiving set. An end gear 10 may be secured to the shaft 6 and the loop rotated by means of a pinion 11, which meshes with the bevel gear 10, and which is secured to a shaft 11, having 20 at its end an operating knob 12. The loop may be incased in the lower part of a cabinet of a receiving set and the shaft 11 extended through the panel on the set. A pointer 13 may be secured to the operating knob 12 to indicate on a convenient scale the direction of 25 orientation of the loop.

In the device illustrated the vertical portions of the turns of the loop are distributed over approximately 240 degrees of the circumference of the imaginary cylinder. This is about the maximum portion of the circumference of the cylinder which can be used to 30 advantage as the horizontal dimension of the few additional turns which could be obtained by covering a large portion of the circumference would be too small to be of much advantage for reception. It will of course be apparent that some of the advantages of my 35 invention may be obtained with the turns of the loop distributed over a smaller portion of the circumference of the cylinder.

The form upon which the loop is wound is preferably constructed entirely of insulating material and fastened together without the 40 use of any metal securing devices, as the use of any metal within the loop introduces losses which should be avoided.

What I claim as new and desire to secure by Letters Patent of the United States, is,—

- 50 1. A receiving loop for radio reception comprising a plurality of spaced turns of wire of different horizontal dimensions so arranged that the vertical portions of a plurality of turns form elements of a single cylinder and none of the horizontal portions of the turns cross a horizontal portion of another turn.

2. A receiving loop for radio reception comprising a plurality of spaced turns of wire of different horizontal dimensions so arranged that the vertical portions of the turns form elements of a cylinder, and are distributed over at least ninety degrees of the circumference of the cylinder and that no horizontal portion of a turn crosses a horizontal portion of another turn. 60

3. A receiving loop for radio reception comprising a plurality of spaced turns of wire of different horizontal dimensions so arranged that the vertical portions of the turns form elements of a cylinder and are distributed over approximately two-hundred and forty degrees of the circumference of the cylinder and that no horizontal portion of a turn crosses a horizontal portion of another turn. 70

4. A loop for radio reception comprising a plurality of spaced turns of wire of different horizontal dimensions so arranged that the vertical portions of a plurality of turns form elements of a single cylinder having a diameter substantially equal to the horizontal dimensions of the turn having the greatest horizontal dimension and that no horizontal portion of a turn crosses a horizontal portion of another turn. 80

5. A receiving loop for radio reception adapted to be mounted to rotate within a cabinet comprising a plurality of spaced parallel turns of wire of different horizontal dimensions so arranged that the vertical portions of all of the turns form elements of a single cylinder having a diameter substantially equal to the horizontal dimension of the turn having the greatest horizontal dimension and that no horizontal portion of a turn crosses a horizontal portion of another turn. 90

6. A receiving loop for radio reception comprising a plurality of turns of wire of different horizontal dimensions so arranged that the vertical portions of the turns form elements of a cylinder and are distributed over at least ninety degrees of the circumference of the cylinder, each of said turns being spaced from the turns adjacent thereto by a distance materially greater than the diameter of the wire, and the horizontal portions of said turns being so arranged that no horizontal portion of a turn crosses a horizontal portion of another turn. 100

In witness whereof, I have hereunto set my hand this 28th day of March, 1924.

RALPH H. LANGLEY.
